(57) **CLAIM**

The ornamental design for a massage device, as shown and described.

DESCRIPTION

FIG. 1 is a front view of a massage device showing my new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof; and,

FIG. 8 is another perspective view thereof.

The dashed or broken lines shown in the drawings depict portions of the massage device in which the design is embodied that form no part of the claimed design.

1 Claim, 8 Drawing Sheets
